UNITED STATES PATENT OFFICE.

JOSEPH C. WHITE, OF NEWTONVILLE, MASSACHUSETTS.

FIREARM.

1,109,383.

Specification of Letters Patent.

Patented Sept. 1, 1914.

Application filed June 23, 1914. Serial No. 846,714.

To all whom it may concern:

Be it known that I, JOSEPH C. WHITE, a citizen of the United States, and resident of Newtonville, in the county of Middlesex and State of Massachusetts, have invented certain new and useful Improvements in Firearms, of which the following is a specification.

My invention relates to firearms and particularly to an improved combination pistol and knife, the object of my invention being to improve the construction of firearms and particularly firearms of the kind referred to.

15 The invention consists of a firearm embodying the novel features of construction and peculiar mode of operation set forth in the following description and particularly pointed out and defined in the claims at the

20 close thereof.

In the accompanying drawings: Figure 1 is a side view of a combined pistol and knife embodying one form of my invention. Fig. 2 is a section on line 2—2 of Fig. 1. Fig. 3 is a section on line 3—3 of Fig. 2. Fig. 4 is a section on line 4—4 of Fig. 2. Fig. 5 is a section on line 5—5 of Fig. 2.

The frame of my improved firearm comprises three plates 1, 2 and 3, and a metal block 4 arranged between the plates 1 and 2 and to which said plates 1 and 2 are fastened by means of screws 5. The plates 2 and 3 are also fastened together by two shouldered rivets 6 which pivotally secure the knife blades 7 and 8 to said frame. The block 4 and plate 1 are shorter in length than the plates 2 and 3 and adjacent one end of the block 4 is a barrel 9 pivotally connected by a pin 10 with a lug 11 provided upon the end of said block. The barrel 9 is normally locked in its closed position by a latch 12 occupying a recess 13 formed in block 4 and pivotally connected with the latter by a pin 14. A spring 15 holds the latch 12 in engagement with a shoulder 16 provided on barrel 9, but by depressing the rear end of latch 12 the latter can be disengaged from barrel 9 leaving the latter free to be swung on pin 10 to the extent of about ninety degrees into the position indicated by dotted lines. When the barrel is thus swung into its open position the breech thereof is exposed and a cartridge can be inserted or an empty shell removed.

The block 4 is formed with a central lon-

gitudinal bore 17 within which is arranged a firing pin 18. One end of the bore 17 is closed by a plug 19 that is held in place by one of the screws 5, and between this plug and pin 18 is arranged a spring 20. The face of block 4 that is next to the plate 1 is formed with a recess 21 within which is arranged a trigger 22 formed from a piece of sheet metal cut and bent to provide a thumb piece 23 projecting out through a slot 24 provided in plate 1, and a spring hook 25 cooperating with the firing pin 18. The hook 25 projects inwardly through a slot 26 into the bore 17 and when the firing pin and trigger are in the positions shown in the drawings the hook 25 is in engagement with the forward end of the enlarged body portion of the firing pin.

After inserting a cartridge in the barrel and closing the latter the piece is fired by grasping it in one hand and, with the thumb of that hand, pulling the trigger rearward. As the trigger moves rearward the hook 25 carries the firing pin 18 with it, compressing the spring 20. When thumb piece 23 reaches the rear end of the slot 24 a deflection 27 provided in said slot at said end, swings the trigger sidewise carrying the hook 25 out of engagement with the firing pin 18 and allowing the spring 20 to throw the firing pin forward against the cartridge. When the trigger is pushed forward again by hand the hook 25 rides over the enlarged body portion of the firing pin and again drops into position in front of said body portion.

The body of the trigger 22 not only fits loosely enough within the recess 21 to allow of its being swung sidewise by deflection 27 as described but when in its normal forward position completely closes the slot 24 thereby excluding dirt, grit and the like from bore 17.

The advantages of my improved firearm 100 reside in its simplicity of construction and ease of operation, and in the safety with which the piece may be handled and carried because the firing pin cannot be left in its cocked position.

What I claim is:

1. A firearm of the character described comprising a frame; a barrel pivotally mounted on said frame; means for holding said barrel in its closed position; a firing pin mounted in said frame; a spring for operating said pin in one direction; a trigger 110

movably mounted on said frame and directly engaging the firing pin to retract the latter when said trigger is shifted on said frame, and means on the frame for operating the trigger to disengage it from the firing pin when said trigger reaches the limit of its pin retracting movement.

2. A firearm of the character described comprising a frame made with a trigger slot having a deflection at its rear end; a barrel pivotally mounted on said frame; means normally locking said barrel in its closed position; a firing pin; a spring for operating said pin in one direction; and a trigger slidably mounted within said frame provided with a finger piece extending through said slot to the exterior of the frame and with a hook coöperating directly with the firing pin, said finger piece being 15 acted upon by the deflection in said slot to shift the trigger sidewise and free the firing pin when the latter is fully retracted by said trigger.

3. A firearm of the character described comprising a frame consisting of two side plates and an intermediate block rigidly

fastened together, one of said plates being formed with a trigger slot having a deflection at its rear end and said block having the face thereof adjacent said slot formed with a trigger recess and said recess being made with a slot in its bottom opening into a longitudinal bore provided within said block; a firing pin mounted within the bore of the block; a spring mounted within said bore for operating the firing pin in one direction; a trigger slidably mounted within the recess of the block provided with a finger piece extending through the slot of the plate to the exterior of the frame and with a spring hook extending through the slot at the bottom of the recess to engage the firing pin, a barrel pivotally mounted on said frame, and means normally locking the barrel in its closed position.

In testimony whereof I have affixed my signature, in presence of two witnesses.

JOSEPH C. WHITE.
